UNITED STATES PATENT OFFICE.

JULIUS KELLER, OF PHILADELPHIA, PENNSYLVANIA, ASSIGNOR TO
PHILADELPHIA PNEUMATIC TOOL COMPANY, A CORPORATION OF
NEW JERSEY.

DESIGN FOR A CASING FOR FLUID-PRESSURE-OPERATED TOOLS.

SPECIFICATION forming part of Design No. 35,333, dated November 26, 1901.

Application filed October 25, 1901. Serial No. 80,019. Term of patent 14 years.

To all whom it may concern:

Be it known that I, JULIUS KELLER, a citizen of the United States, residing in the city and county of Philadelphia, State of Pennsylvania, have invented and produced a new and original Design for a Casing for Fluid-Pressure-Operated Tools, of which the following is a specification, reference being had to the accompanying drawings, forming part thereof.

The leading feature of my design for a casing of a fluid-pressure-operated tool is a body portion having projections thereon and handles extending rearwardly at an angle from said projections.

Figure 1 represents a perspective view of a casing of a fluid-pressure-operated tool em-

bodying my design. Fig. 2 represents a plan view of Fig. 1.

In the drawings, A designates a casing for a fluid-pressure-operated tool, the same having the projections B thereon. C designates handles extending rearwardly at an angle from said projections.

Having described my invention, what I claim as new, and desire to secure by Letters Patent, is—

The design for a casing of a fluid-pressure-operated tool substantially as herein shown and described.

JULIUS KELLER.
